(No Model.)

H. WATERSON.
HANDLE FOR VELOCIPEDES.

No. 445,914.

Patented Feb. 3, 1891.

Henry Waterson

UNITED STATES PATENT OFFICE.

HENRY WATERSON, OF ASTON, ENGLAND.

HANDLE FOR VELOCIPEDES.

SPECIFICATION forming part of Letters Patent No. 445,914, dated February 3, 1891.

Application filed July 31, 1890. Serial No. 360,527. (No model.) Patented in France January 28, 1890, No. 203,404.

To all whom it may concern:

Be it known that I, HENRY WATERSON, of Aston, England, a subject of the Queen of Great Britain, have invented certain new or 5 Improved Pneumatic or Air-Buffer Handles or Grips for the Steering-Handle Bars, Brake-Levers, or other Parts of Bicycles, Velocipedes, and other Carriages, (for which I have obtained Letters Patent in France, No. 10 203,404, dated January 28, 1890,) and I do hereby declare that the following is a full, clear, and exact description of the invention, which will enable others skilled in the 15 art to which it appertains to make and use the same.

This invention has for its object to provide an elastic, compressible, hollow handle or grip for a bicycle or other wheeled vehicle, and to provide means whereby the hollow handle or 20 grip will be restored to its normal bulged condition after being compressed by the hand and then released from pressure. To accomplish this object my invention involves the 25 features of construction, the combination or arrangement of parts, and the principles of operation hereinafter described and claimed.

I will describe and illustrate my invention in connection with a handle or grip for the steering-handle bar of a bicycle. I form the 30 handle or grip of vulcanized india-rubber and construct it of an inner cylindrical tube and an outer air-chamber, preferably of a bulbous or ellipsoidal figure, surrounding the greater part of the said inner cylindrical 35 tube, the ends of the air-chamber being closed. The internal diameter of the inner cylindrical tube of the handle or grip is less than that of the handle-bar on which it is fixed, so that by drawing the said inner cylinder upon the 40 handle-bar it is so expanded that its elasticity binds it firmly on the handle-bar; or the non-vibratory handle or grip may be used without the continuous internal cylindrical tube for gripping the handle-bar. In this 45 case the bulbous or ellipsoidal vulcanized-india-rubber air-chamber or air-cushion has short cylindrical ends or collars, which are drawn upon and fixed to the handle-bar in any convenient way. A small air valve or 50 perforation may be used in the air chamber or cushion for inflating the same.

Figure 1 of the accompanying drawings represents in elevation, and Fig. 2 in longi-

tudinal section, a non-vibratory handle or grip of the first-described kind; and Figs. 3 and 4 represent cross-sections of the same, taken, respectively, on the dotted lines *a a* and *b b*, Fig. 1. Figs. 5, 6, 7, and 8 represent modified handles or grips, as hereinafter described.

The same letters of reference indicate the same parts in the several figures of the drawings.

I will first describe the handle or grip represented in Figs. 1, 2, 3, and 4.

c is the cylindrical handle-bar.

d is the inner cylindrical tube of the handle or grip, which is drawn upon the said handle-bar *c*, and *e* is the closed air-chamber or air-cushion surrounding the said inner cylindrical tube *d*, the said cylindrical tube and air chamber or cushion being made of vulcanized india-rubber, which is elastic and can be compressed by the hand, while the contained air will restore the handle or grip to its normal bulged condition after being compressed by the hand and then released from pressure. The said air-chamber or air-cushion *e* have the bulbous or ellipsoidal figure represented, the diameter of the said chamber being greatest at its middle (see the section, Fig. 3) and diminishing as it approaches the closed ends of the chamber; but I do not confine myself to any particular shape of the air-chamber or air-cushion of the handle or grip. The contraction of the long continuous inner tube *d* of the handle or grip after it has been drawn upon the handle-bar *c* suffices to hold the said handle or grip firmly upon the handle-bar. The said grip may, however, be further secured in its place by india-rubber or other cement.

I inflate the closed air chamber or cushion *e*, or produce the required pressure of air within it to sufficiently resist the grip of the rider's hand in the following way: At the middle and projecting on the inner side of the air-chamber *e* a block or thickened piece *e²*, of india-rubber, is made, as in the ordinary manufacture of inflated india-rubber articles. Through this block or thickened piece *e²* a fine hole or perforation is made, and into this hole the fine and pointed tubular nozzle of an air-syringe is passed, and by working the said syringe the closed air-chamber is inflated to the required degree. On withdrawing the

nozzle of the air-syringe from the fine hole in the block e^2 the elasticity or contraction of the said block closes air-tight the said fine hole and the air-chamber or air-cushion is preserved in its inflated state. By interposing between the hand of the rider and the metallic (or other) steering-bar c of the velocipede the air-chamber or air-cushion e the vibration or tremor of the velocipede is not transmitted to the hand or is transmitted only to a limited extent.

Fig. 5 represents in section a modified handle or grip constructed according to my invention. In this modification the outer part 15 of the handle has a bulbous figure, and its end is nearly closed, and the air-chamber or air-cushion e is confined to the bulbous outer part, so that while the air-chamber part e of the handle is capable of a limited yielding when gripped the inner or chamberless part 20 is solid or non-yielding. The rider can thus grip either the yielding or non-yielding part of the handle, as he may require. The air-chamber at the outer part of the handle is 25 inflated by passing the nozzle of an air-syringe through a fine hole in the block e^2 , as hereinbefore described, and a hole a^2 in the nearly-closed end of the handle permits of the escape of air when the tubular part d is 30 drawn onto the end of the handle-bar c .

Fig. 6 represents in elevation and Fig. 7 in longitudinal section a non-vibratory handle or grip in which the inner cylindrical tube is omitted, and the vulcanized india-rubber air 35 chamber or cushion has tubular ends or collars for fixing it to the handle-bar instead of a continuous internal tube, as in the handles or grips before described. In this modified handle or grip the bulbous or ellipsoidal air 40 chamber or cushion f has cylindrical ends or collars g , which are drawn upon the handle-bar c and fastened thereto, so as to close both ends of the handle or grip f and form the said handle or grip into an air chamber 45 or cushion.

The fastening of the ends g of the chamber f upon the handle-bar may be effected by coiling fine wire, catgut, or other cord around the said ends, as represented at h , or by 50 means of metallic clips or bands made to encircle and bind the said ends of the chamber upon the handle-bar.

In order the more efficiently to bind the tubular ends g upon the handle-bar, the 55 parts of the handle-bar on which the tubular ends g are fixed may be grooved or have a screw-thread cut upon them, into which grooves or screw-thread the tubular ends are forced by the binding wire or cord, as represented at i , Fig. 8.

Those parts of the handle-bar on which the tubular ends or collars g fit may be coated with india-rubber cement, in order the more effectively to make the contact between the 65 said tubular ends g and handle-bar airtight.

To prevent the possibility of failure in the

action of the air chamber or cushion f , a small automatic valve opening inward, as represented at k , Fig. 7, may be employed. 70 Should any air escape by pressure on the air-chamber f , when this pressure is removed the said air-chamber f expands to its normal shape, drawing in air at the valve k .

The valve k , Fig. 7, and the construction 75 and appliances hereinbefore described for introducing compressed air into the chambers e and f may be dispensed with, as by making the walls of the closed chambers of the grip of sufficient thickness any required 80 resistance to compression by the hand may be obtained and the restoration of the grip to its normal figure on the relaxation of the pressure of the hand effected.

The new or improved non-vibratory handles or grips described and illustrated may 85 be applied to the steering-handle bars and brake-levers and other handles or hand-gripped parts of velocipedes generally, and also to the holding-handles of carriages, such 90 as bath-chairs and perambulators.

In the manufacture of the elastic compressible hollow handle the inner wall is formed from a tube of unvulcanized rubber, and the outer wall is built up, making the 95 joints at the ends by pieces of canvas, and leaving a cavity between the tube and outer wall. The cavity before being closed is supplied with a quantity of water or any fluid that will expand when heated, and the whole 100 is then vulcanized in a mold. The hollow handle is subsequently inflated, which is 105 preferably effected by an instrument made to pierce the outer wall of the handle for working up an air-pressure therein. When the air-forcing instrument is withdrawn, the hole made thereby closes and makes a tight joint.

Having now particularly described and ascertained the nature of my invention and 110 the manner in which the same is to be performed, I declare that I claim as my invention—

1. A hollow, elastic, and compressible india-rubber handle or grip for a bicycle or other vehicle, having an air-chamber containing 115 confined air to form an air-cushion, said air serving to restore the handle or grip to its normal bulged condition after being compressed by the hand and then released, substantially as described.

2. A hollow, elastic, and compressible india-rubber handle or grip for a bicycle or other vehicle, having an air-chamber and an air-inlet opening for inflating the handle or grip, 125 so that the confined air forms a cushion and serves to restore the handle or grip to its normal bulged condition after being compressed by the hand and then released, substantially as described.
